United States Patent

Des. 237,374
Patented Oct. 28, 1975

237,374

TIRE

John A. Hutz, Orlando, Fla. and Maurice L. Pules,
Akron and William W. Wolford, North Canton, Ohio,
assignors to The Goodyear Tire & Rubber Company

Filed Sept. 9, 1974, Ser. No. 504,578

Term of patent 14 years

Int. Cl. D12—15

U.S. Cl. D12—136

The figure is a perspective view of a tire showing our new design, it being understood that the design is repeated throughout the circumference of the tire as shown schematically by solid lines, the opposite side being substantially the same as that shown.

We claim:

The ornamental design for a tire, substantially as shown and described.
